[57] ABSTRACT

A serial printing mechanism with a constantly rotating type lever assembly in which the type lever selected for printing performs, within a predetermined angular range, a printing movement directed towards the axis of rotation. The type lever assembly in the form of a rim-shaped magazine rotates immediately in front of the printing point, the axis of rotation extending vertically to the printing point. The respective type lever selected for printing performs a printing movement directed inwardly towards the axis of rotation. Approaching said axis of rotation asymptotically, printing is effected exactly on the axis of rotation or in its immediate vicinity.

PRINTING MECHANISM FOR SERIAL DATA RECORDING

BACKGROUND OF THE INVENTION

The present invention relates to a printing mechanism for serial data recording in which the printing unit consists of a type lever magazine arranged in a rim-shaped manner in relation to the axis of rotation and which rotates at constant speed, and in which the individual type levers selected for printing are caused to perform a printing movement towards the axis of rotation within a predetermined angular range via a cam arrangement.

A printing mechanism of this kind is described in U.S. Pat. No. 3,417,847 and U.S. Pat. application Ser. No. 754,578 now allowed, both assigned to the assignee of this invention. In the embodiments described there, there is provided a plate-shaped type lever magazine horizontally rotating below the printing platen, from which the selected type levers are lifted in the direction of the axis of rotation and strike the platen. 15

By the arrangement of the plate-shaped type lever magazine below the platen, virtually only web-type and sheet recording media can be used because the position of the type lever magazine requires that the recording medium be led around the platen. 20

In many cases, however, it is necessary to letter stiff recording media such as ledger cards or savings bank pass books which are difficult to bend. In such cases an arrangement is required which permits a straight guidance of the recording medium. 25

A printing mechanism which meets this requirement is disclosed in U.S. Pat. No. 3,289,805. Here also a constantly rotating type lever magazine is provided which, however, is designed in the manner of a cage and, in rotating around a vertical axis, is arranged before the platen. The respective type lever selected for printing strikes outwardly and hits the platen at the moment it passes the printing point. 30

This conventional printing mechanism is disadvantageous in that, due to the volume of the basket increasing with the number of type levers, the number available for printing is limited depending on the rotational speed because, in order to achieve a clean print, a certain relative velocity between the stationary recording medium and the circulating types must not be exceeded. 35

Another printing mechanism meeting the above-mentioned requirements is disclosed in U.S. Pat. 2,833,387. Here the stationary assembly of type levers is grouped in the manner of a basket around the central axis of the printing unit arranged vertically in relation to the printing point, the type levers being pivoted in such a manner that, hitting inwardly, they strike on the extension of the central axis. 40

Apart from the conventional type lever selection and print control which enable only a relatively low sequence of characters, this arrangement has the very significant disadvantage that, as a result of the type levers being stationary, each printing type must be soldered-on in a different angle in order to achieve upright printing. 45

SUMMARY OF THE INVENTION

The above-mentioned disadvantages of these conventional printing mechanisms are avoided by the printing mechanism according to the invention, which

is characterized in that the type lever magazine rotates in parallel to and closely before the printing point, wherein in the normal path of rotation, the type levers assume a position pointing away from the printing point, wherein the respective type lever selected for printing performs a printing movement directed asymptotically towards the axis of rotation, and wherein printing is effected whenever the respective type lever stands vertically over the printing point. 5

Using the inventive printing mechanism, it is possible on the one hand to print stiff recording media, and on the other hand, to double the number of characters without any appreciable changes of conditions at the moment of printing. In addition, all type levers may be provided in a conventional manner with unidirectional types. 10

BRIEF DESCRIPTION OF THE DRAWINGS

The invention will now be described in more detail with reference to two embodiments thereof in conjunction with the accompanying drawings in which:

FIG. 1 is a schematic cross-sectional view of a printing mechanism according to the invention taken along line I — I of FIG. 2; 20

FIG. 2 is a front view of the printing mechanism of FIG. 1, with the cover portion being shown as if it were transparent; 25

FIG. 3 is a partial view of the shape of the printing cam; and 30

FIG. 4 shows a modification differing with respect to the relative position of the printing unit of FIG. 1 in relation to the platen. 35

DESCRIPTION OF THE PREFERRED EMBODIMENT(S)

In the printing mechanism according to the invention as shown schematically in FIG. 1, the printing unit 1 comprises on the one hand a pot-like body of revolution 2 provided with a hollow shaft butt 2a and, on the other hand, a cover 3 shielding the body 2, in which, pivoted on an annular axle 5, type levers 4 are held in radial guide slots 3a. The cover 3 having a centric opening 3c is permanently connected with the body 2 in a manner not shown. 40

The printing unit 1 is rotatably mounted for example in a pillow block 9 of a carriage device (not shown) via which, in known manner, the printing unit 1 is guided in stepped fashion or continuously along a printing base. 45

This printing base may be a printing platen 13 with a curved surface or a plane printing rail. In each case, the printing unit 1 is arranged so that the axis of rotation extends vertically in relation to the printing point, i.e. as shown, the line of print and the platen are horizontal, with the axis of rotation of the printing unit being also horizontal but perpendicular to the line of print and the printing platen 13. 50

The distance between the printing base, i.e., the platen 13 in the embodiment of FIG. 1, and the front surface 3d of the cover portion 3 is exactly such as to insure that the recording medium (media) 14 can be inserted without hindrance, and that there is a certain safety distance between the recording medium and the front surface 3d. 55

The printing unit 1 is rotated via a toothed-gear drive 11, 12 by a uniformly driven splined shaft 10. 60

In the normal (rest) condition, the type levers 4 mounted in the cover 3 rest on a concentric track 3b against which they are held during the rotation of the printing unit 1 by the effective centrifugal force.

Supported in the pot-like body of revolution 2 is a cam unit 6 which is guided by a shank 6e slidably supported in the hollow shaft butt 2a. This shank 6e projects beyond the shaft butt 2a which is flush with the pillow block guide. Stationarily arranged at this free end is a flange-like adjusting ring 8 resting flatly against the pillow block 9. Via an eccentric device 8a shown only symbolically, the adjusting ring 8 can be twisted within certain limits against the pillow block 9. Thus, it is accomplished that the cam unit 6, unlike the other parts of the printing unit 1, is stationary and can be adjusted from outside via the eccentric device 8a.

The cam unit 6 serves on the one hand to secure the type levers 4 in their normal path of rotation and, on the other hand, to lead the type levers 4 selected for printing to the printing point and back to the path of rotation.

To this end, the unit 6 has a ring-shaped guideway 6a (FIG. 2) by which the type levers 4, in connection with the type lever support (i.e. concentric track) 3b, are positively guided. This kind of guidance is necessary because, if at rest, i.e., rotational motion has ceased for example in a stepped motion operation, the type levers 4 of the upper range, i.e., those winding up in a position at the top most part of the print unit 1, which otherwise would normally be held against the track 3b by the centrifugal force of the rotating printing unit, would fall towards the center. If the printing mechanism were restarted, this would inevitably result in destruction of the printing unit unless measures are taken such as ring-shaped guide 6a.

As shown, the guideway 6a is interrupted in the lower part of FIG. 2. At this point, permanently connected to the cam unit 6, there is arranged a selecting station 7 designed, for example, according to the U.S. Pat. application Ser. No. 828,176, filed May 27, 1969, by which the type levers 4 intended to perform printing are magnetically lifted out of the normal path of rotation. In the course of printing unit rotation, the selected type lever 4 is finally deflected as illustrated in FIG. 1 by the dotted type lever 4, whereby its free end is moved into the range of a cam 6b leading the type lever 4 to the printing point. This printing cam is designed so that, in an angle of rotation of about 160° from the selecting point, the respective type lever performs a movement directed asymptotically towards the axis of rotation of the printing unit 1. As a result, the type lever 4 is accelerated to a final velocity which is determined by the required printing energy. Shortly before the respective type lever 4 stands vertically over (in front of) the printing point i.e., the point on the line of print at which the selected type lever strikes the platen (FIG. 2), the printing cam 6b ends, so that the type lever covers the last distance to the striking of the type 4a against the recording medium 14 in free flight. Striking takes place exactly at the instant the type lever stands vertically over the printing point, as shown in FIG. 2. In the embodiment shown in FIGS. 1 and 2, the printing point lies exactly on the extended axis of rotation of the printing unit 1, the selected type lever having its free end pass through the center of rotation of the printing unit to arrive at the printing point. Thereby, even if the rotational speed of the printing unit 1 is very high, the

movement of the type 4a relative to the recording medium 14 is practically zero so that clean printing is insured in each case.

During further rotation, the type lever 4, in rebounding after the printing, is caught by a resetting cam 6c and forcibly reset to the normal path of rotation. The schematic representation of FIG. 2 shows only one of the required two cam surfaces effecting a positive resetting force on a selected type lever.

For clarity and since the principle of such forced guidances is well-known, the second cam has been omitted in FIG. 2.

In reset area of a recess 6d, the resetting cam 6c joins the guideway 6a by which the respective type lever 4 is rest to the normal path of rotation. Via a guideway section 6a' subsequently arranged in the direction of rotation, a forced guidance is effected again in connection with the type lever support 3b (FIG. 1), whereby it is insured that the respective type lever 4, stably enters the area of the selecting station 7 for a possible new selection.

As can best be seen from FIG. 1, the shank 6e is provided with a longitudinal bore hole 6f through which the control lines 7a of the selecting station 7 (not visible in FIG. 1) are lead outwardly.

In a cross-section through FIG. 1, the partial view of FIG. 3 shows essentially the cam unit 6 and specifically the design of the printing cam 6b. In order to obtain a favourable, i.e. not too steep curvature of the cam, the track on which the type levers slide is designed so that the cam 6b engaging the free end of the type lever at the beginning has a curvature directed more closely towards the fulcrum of the type levers 4, as shown in FIG. 3. Thus, the cam can be made flatter. At the same time, the force components acting upon the respective type levers assume favourable values. In addition, the abrasion of the type levers sliding on the curved track is distributed over a greater area, so that wear is minimized.

The resetting curve 6c is designed correspondingly, except that, in accordance with its function, it engages the middle of the type lever at the beginning and acts upon the free end of the type lever 4 towards the end, i.e., with the transition into the guideway 6a.

FIG. 4 shows schematically a modified form of the embodiment described so far.

As already mentioned and as is well-known, in type lever printing mechanism, a relative movement between the recording medium and the printing type is allowed up to a speed of about 3 m/sec. without resulting in any noticeable reduction in the printing quality.

In the embodiment shown in FIG. 4, using this effect, printing is no longer performed on the extended axis of rotation of the printing unit but above this axis at a distance x. For the quantity of x, the following relation applies:

$$x = V_{\text{rel.}} \cdot 30/\pi \cdot n \text{ (mm)}$$

where

$V_{\text{rel.}}$ is the permissible relative velocity in mm/sec. between type 4a and recording medium 14 at the moment of printing, and

n is the constant rotational speed in r.p.m.

By this measure, the radius of the annular axle 5 can be increased by the distance x with the length of the type levers remaining unchanged. Thus, compared to the embodiment shown in FIG. 1, a correspondingly greater number of type levers can be accommodated

within a type lever assembly, with the limiting effect being primarily determined by the radially extending guide straps between the individual type levers, which, for reasons of strength, must not fall below a certain thickness in the direction of the axis of rotation.

What is claimed is:

1. A printing mechanism for serial data recording comprising:

a platen;

a printing point disposed in a given plane tangential to said platen; and

a printing unit including

a pot-shaped body of revolution having a first hollow shaft extending therefrom in a direction away from said printing point and a cover for said body of revolution opposite said first shaft adjacent said printing point,

means coupled to said first shaft to rotate said first shaft, said body of revolution and said cover about an axis of rotation disposed perpendicular to said given plane,

a plurality of type levers disposed within said cover for rotation therewith, each of said type levers having one end that is free for movement toward said printing point carrying type to be printed and the other end is pivotably mounted to said cover in a spaced radial relationship with said axis of rotation,

an opening in said cover disposed coaxial of said axis of rotation and in a printing relationship with said printing point and said one end of each of said levers, and

a cam unit means disposed within said body of revolution in a cooperative relation with said one end of each of said type levers to control the movement thereof so that a selected one of said type levers is moved first toward said axis of rotation and then passes through said opening parallel to said axis of rotation to strike said printing point perpendicular to said given plane to effect a printing at said printing point,

said cam unit means being adjustably mounted within said first shaft by means of a second hollow shaft.

2. The printing mechanism according to claim 1 wherein said cover includes guide slots directed radially to said axis of rotation for guiding said type levers through said opening, and a type lever support track disposed concentrically about said axis of rotation for maintaining said type levers in a normal rotating position.

3. The printing mechanism according to claim 1 wherein said cam unit means includes a guideway concentrically disposed about said axis of rotation, a printing cam and a resetting cam, each of said printing cam and said resetting cam acts upon said one end of each of said type levers in cooperation with said guideway to effect a printing of a selected lever, said guideway being interrupted only at a given location to enable type lever selection.

4. The printing mechanism according to claim 3 wherein a selecting station is provided at said given location for selecting desired ones of said type levers, and wherein control lines to said selecting station are led through said second shaft.

5. The printing mechanism according to claim 3 wherein said printing cam provides a support for a selected one of said type levers that moves toward the pivoted end thereof in effecting a printing and said resetting cam provides a support for said selected one of said type levers that moves back towards said one end thereof to effect a return of said selected one of said type levers to a normal rotation.

6. The printing mechanism according to claim 1, wherein said printing point is coincident with an extension of said axis of rotation.

7. The printing mechanism according to claim 1, wherein said printing point is spaced radially a predetermined distance from an extension of said axis of rotation.
